UNITED STATES PATENT OFFICE.

JOHN ZELLER, OF MOBRIDGE, SOUTH DAKOTA.

CLAMP-APPLIER.

1,319,746.

Specification of Letters Patent. Patented Oct. 28, 1919.

Application filed March 21, 1919. Serial No. 284,060.

To all whom it may concern:

Be it known that I, JOHN ZELLER, a citizen of the United States, and a resident of Mobridge, in the county of Walworth and 5 State of South Dakota, have invented a new and useful Improvement in Clamp-Appliers, of which the following is a specification.

This invention relates to a clamp applier and aims more particularly to provide a device of this nature which will be simple in construction, resulting in the consequent economy in manufacture.

Attention is invited to the annexed sheet of drawing wherein—

15 Figure 1 is a side perspective of my improved clamp applier in operation,

Fig. 2 is a side elevation partly in section,

Fig. 3 is a section on the lines *a—a* of Fig. 1,

20 Fig. 4 illustrates the tool after having almost completed the application of the clamp, and

Fig. 5 the clamp in applied position.

In these views the reference numeral 1 25 designates a rod which is provided at one end with a handle 2 and screw-threaded throughout its entire length as at 3. A nose 4 is pivotally mounted upon the opposite end of the rod as at 5 and is provided with a 30 grooved portion 6 adapted for engagement with a wire. An interiorly screw-threaded collar 7 is mounted upon the rod and is adapted to be moved along the same by virtue of its engagement with the screw 35 threads upon the rod, when the collar is held against rotative movement.

The collar 7 is provided with openings extending parallel to its main bore, such openings being provided through the ends of the 40 collar as at 8 and 8' upon opposite sides of the rod 1.

Further openings 9 and 9' are provided in said collar running at right angles to the openings 8 and 8', such openings 9 and 9' 45 communicating at their inner ends with the openings 8 and 8' and extending through to the outer face of the collar 7. The openings 9 and 9' are interiorly screw-threaded and are provided with winged bolts 10 and 11 50 which are also screw-threaded and adapted

to be engaged with the screw threads of the openings 9 and 9'. It will be noted that the ends of the winged bolts are grooved as at 12 for the purpose of securing such a purchase upon the ends of the wires as to positively prevent withdrawal movement of the wires relatively to the collar when tension is placed upon the latter by turning the screw.

It will be understood that wire clamps are 60 sold ready to apply and that such clamps are usually formed in the shape of the letter U.

It will now be noted that in operation all that is necessary to be done is to engage the base of the wire clamp with the grooved 65 portion 6 of the nose 4, as at 13, after having threaded the ends 14 through such base around the hose 15. The ends 14 are then passed through the openings 8 and 8' and drawn through the same as far as practical 70 by hand, upon which the winged bolts 10 and 11 are tightened down so as to retain the ends 14 in position. It will be understood that during these preliminary operations that the tool is in the position illustrated in Figs. 1 and 2. The handle 2 is now rotated so as to draw the collar 7 and consequently the ends 14 of the wire clamp toward it and the clamp firmly around the 75 hose 15. When the proper degree of tension has been exerted upon the clamp the handle 2 is rocked anticlockwise around its nose 4, the engagement between the wire 13 and grooved portion 6 acting as a pivot point, until the position illustrated in Fig. 80 4 has been reached. When the clamp has been applied to this point it will be understood that the same will remain in position of its own initiative and the surplus length of wire 14 may now be clipped to the length 90 desired and bent around the base of the clamp as illustrated in Fig. 5 by any suitable device.

I claim:—

A clamp affixer including a rod, a collar 95 mounted upon said rod, means for engaging a wire secured to the front end of said rod, such collar being provided with openings extending parallel to the bore of said collar, such collar being provided with further 100

openings extending at right angles to the first-named openings between the side walls of the collar and the first-named openings, such latter openings being interiorly screw-threaded and winged bolts provided with grooved ends mounted within such latter openings adapted to engage and retain with

their inner ends wire adapted to be passed through the first-named openings.

JOHN ZELLER.
